HAMILTON LINDSAY, OF CLEVELAND, OHIO, ASSIGNOR TO LINDSAY WIRE WEAVING COMPANY, OF CLEVELAND, OHIO, A CORPORATION OF OHIO.

METHOD AND MEANS FOR WEAVING WIRE FABRIC.

Application filed March 10, 1926. Serial No. 93,583.

One of the most difficult problems to overcome in the manufacture of paper with Fourdrinier paper making machines is the elimination of water marks which extend 5 longitudinally of the paper and for substantially the entire length of the roll. This problem has necessitated the expenditure of considerable time and money to locate the cause of the water marks, and to provide a 10 remedy therefor. I have found that the objectionable water marks are due to slight displacement of warp wires from the plane of the wire belt, and that such almost imperceptible displacement can occur during 15 the making of the fabric, while the weft wires are being driven into the work. This displacement I have also found has been due to slight inaccuracies of construction in the reed, which are almost impossible to eliminate. For example, if the winding tape 20 which is used for holding the reed dents in proper spaced relationship is tighter in some places than in other places, then uneven spacing between the dents will occur. Moreover, if the pitch which is used for holding 25 the binding tape in place should harden or solidify unevenly throughout the length of the reed, then such unevenness would also tend to affect the smoothness of the weave. 30 Due to the particular construction of the reed making machinery such unevenness is apt to occur for a continuous portion of the reed; further the displacement is frequently so great as to render the reed useless. Moreover 35 there are other causes that affect the degree of smoothness in a direction transversely of the warp, such as the degree of hardness of the weft wires. Heretofore comparatively soft wire had to be used for the weft, 40 but this makes a cloth which is not as strong in the body as that which is woven with a comparatively hard wire. With my invention I obtain exceptionally smooth results without necessitating a fine degree of accuracy 45 in wire temper, and therefore without requiring the use of a comparatively soft weft wire.

The principal object of the present invention is to provide means for eliminating 50 slight displacement of the warp wires during the formation of the fabric without materially altering the present loom construction.

A further object of the present invention 55 is to provide means for making wire cloth

wherein the corrugated effect due to inaccuracies in reed construction is eliminated. In this connection my invention contemplates the provision of means which will enable smooth cloth to be woven without 60 correcting the inaccuracies in the reed. Thus I may use reeds which heretofore have been regarded as worthless.

The preferred means for carrying out my invention is shown in the drawings wherein 65 Fig. 1 is a front elevation of a loom embodying my invention; Fig. 2 is a perspective view of a portion of the loom showing more in detail the use of my invention; Fig. 3 is a cross section taken through the bat- 70 ten on a plane indicated by the line 3-3 in Fig. 2; Fig. 4 is a diagrammatic view showing the relationship of the batten swing to the shed and work; Fig. 5 is a section on an enlarged scale showing more in detail the ef- 75 fect of engaging the wire on the underside, while the batten is near the forward end of the swing; Fig. 6 is a diagrammatic view showing a cross-section through the woven 80 fabric and indicating on an enlarged scale 85 the effect of displacement of some of the warp wires.

In the drawings a loom frame is indicated at 10 as pivotally supporting a batten frame 11 which carries the reed indicat- 85 ed in general at 12. The reed is shown as being held in position by clamping strips 13 and 14 which are secured to the batten frame and as extending for substantially the entire length of the reed. The practice hereto- 90 fore has been to keep the upper edge of the lower strip beneath the bottom of the lowermost exposed portion of the reed dents. Under such conditions the warp wires in certain regions are apt to be displaced out 95 of the plane of the fabric of the cloth so that when fabric is removed from the loom it assumes a corrugated appearance which is illustrated on an enlarged scale in Fig. 6. The corrugations thus extend transversely 100 of the warp wires, and hence when a belt which is made from such fabric is in use, the corrugated portions are flattened due to the pressure placed upon the belt while it is passing across the suction box; but since the 105 belt is prevented from stretching laterally by the side rails, then the belt has a tendency to pucker and thereby to cause the formation of water marks which extend longitudinally of the paper.

I have found that such displacement of the warp wires may be overcome by exerting pressure on the underside of the work, and entirely across the work about the same time 5 at which a weft wire is being driven into the work. A simple and convenient way of accomplishing this is to extend the lower clamping strip above the lowermost exposed portion of the reed dents, so that the warp 10 wires adjacent the work will be raised slightly by contact with the strip at about the same time that each weft wire is driven into the work. The upper edge of the strip 14 may be curved and polished to provide a 15 smooth surface, and thereby to prevent abrasive action upon the wires.

The height to which the upper edge of the strip may be adjusted with reference to the bottom of the reed depends upon the relative 20 position of the bottom of the reed to the work when the batten is at the end of the forward swing. I have found that best results can be accomplished by having the upper edge of the strip sufficiently high that 25 the work is engaged by the strip while the weft wire is an inch or two away from the work. This contact between the strip and the wires occurs while the wires are under tension, and therefore causes the warp wires 30 to be bowed slightly upwardly, as shown in Fig. 5, which bowed portion is automatically moved along like a wave as the cloth beam is slowly wound up during the weaving process.

35 In practice the weft wire 20, indicated in Fig. 5, to be driven into the work is on the side of the wave toward the loom, so that as each succeeding weft wire is driven into place, the preceding weft wires are forced 40 over the crest and then down the side away from the loom. As a result the fabric is exceptionally smooth across the entire width.

The manner in which the work is engaged 45 is best illustrated in Fig. 4 wherein the swing of the batten is indicated diagrammatically and wherein the arc 21 described by the upper edge of the strip 14 is shown as intercepting the line of the lower warp wires at 22 before the batten reaches the end of the 50 forward swing.

In Fig. 5 I have shown diagrammatically in full lines the strip 14 in engagement with the warp bank 30. The broken lines 30^a il-

lustrate the position of the warp bank when the strip is in the position shown at 14^a.

55

An important advantage of my invention is the fact that I have been able to obtain fabric having an exceptional degree of smoothness and that such fabric can be woven without making extensive changes in the construction of the loom and also without changing the construction of the reed. Moreover, I have been able with the use of my invention to utilize reeds which heretofore have been regarded as useless, due to inaccuracy in the spacing of the dents which occur during the manufacture of the reed.

60

65

I claim:

1. A method of weaving wire fabric comprising laying a weft wire, driving it toward the work, engaging the warp wires on the underside thereof and in the region of the last weft wire before the weft wire reaches the work and progressively increasing the pressure with which the warp wires are engaged on the underside until the maximum pressure is reached when the weft wire is brought to rest within the work.

70

2. In a loom, the combination with a frame, of a batten pivotally mounted thereon, a reed carried by the batten, a member positioned on the batten in front of the reed and in close proximity thereto and projecting above the bottom of the lowermost exposed portion thereof, warp wires extending through said reed said member being arranged to engage the underside of said warp wires and to exert pressure thereon during the forward swing of the batten, and to release the pressure during the backward swing.

75

3. A step in the method of weaving wire fabric, comprising engaging and slightly raising the warp bank at the moment of beat-up and in the region of the last few weft wires.

85

4. A step in the method of weaving wire fabric, comprising engaging the underside of the warp bank at the moment of the beat-up, exerting sufficient pressure to stretch the warp bank substantially the full width of the work, and then releasing the pressure immediately after the moment of beat-up.

95

100

In testimony whereof, I hereunto affix my signature.

HAMILTON LINDSAY.
